Primary Examiner — Marianne Pandozzi*Assistant Examiner* — Jae Liang(74) Attorney, Agent, or Firm — Global IP Counselors, LLP(57) CLAIM

The ornamental design for a food bowl portion with support, as shown and described.

DESCRIPTION

FIG. 1 is a top perspective view of a food bowl portion with support showing our new design;

FIG. 2 is a lower perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof; and,

FIG. 8 is a bottom plan view thereof.

The dashed lines depicted in FIGS. 1-5 and 7-8 are for illustration of environmental subject matter only and form no part of the claimed design. The dot-dash lines shown in FIGS. 1-8 are for illustration of the boundary between claimed subject matter and unclaimed subject matter only and form no part of the claimed design.
